UNITED STATES PATENT OFFICE.

HENRY W. O'NEILL, OF BROOKLYN, NEW YORK, ASSIGNOR TO WESTERN ELECTRIC COMPANY, INCORPORATED, OF NEW YORK, N. Y., A CORPORATION OF NEW YORK.

SIGNALING SYSTEM.

Application filed November 20, 1922. Serial No. 601,952.

This invention relates to improved means for signaling over transmission lines and is particularly applicable to transmission lines composed for simultaneous telephony and 5 telegraphy.

The principal object of this invention is to improve two-way signaling over a long transmission line.

In accordance with the foregoing and 10 other objects of this invention, a system is provided wherein currents of different and relatively high frequencies are superimposed on one another to selectively actuate cooperating means at either end of a long transmission line and actuate the signaling means 15 thereof. Inductive effects and surges that may be present on the composited line will therefore not interfere with the proper functioning of the signaling means.

One feature of this invention resides in 20 the control of signaling apparatus in a composited system over the sleeve conductor of the line.

Another feature is embodied in the provision in such a system of a plurality of high speed alternating current relays which are selectively responsive to currents of different 25 relatively high frequencies cooperating with one another to control the application of ringing frequency current to the line.

Another feature of this invention resides in the provision of means normally bridged across the line and respectively responsive to currents from either end of the line to 30 control current supplying means which is effective in actuating the signaling apparatus.

A further feature of this invention resides in the provision of high speed means to apply suitable signaling current to the line 35 and to prevent low frequency currents from reaching the line.

The invention will be readily understood from the following description and by reference to the accompanying drawings in 40 which Fig. 1 shows a transmission line terminating at suitable switching points, while Fig. 2 shows another embodiment of the invention.

In the following description, it will be assumed that the key 100 is controlled by an operator at a station designated by "A" and that the key 150 is controlled by an operator at a station designated by "B," and further,

that the operator at A desires to signal the operator at B.

The operator at A inserts plug 101 into jack 102 and, in so doing, disconnects the operating winding of the signal 103 from the tip and ring conductors of the line, and then actuates the key 100, whereupon a circuit is established from ground, through the winding of relay 104, sleeve conductor 105, sleeve contacts of jack 102 and plug 101, and thence to ground through the contacts of key 100 and battery 106. Relay 104 operates in this circuit and connects at its armatures and front contacts the alternating current sources 107 and 108 which, for descriptive purposes, will be assumed to be 1300 and 1700 cycles, respectively, to the tip and ring conductors 70 of the transmission line C.

At the distant end of the line C, alternating current high speed relays 109, 110 and 111 are connected in series and are bridged across the tip and ring conductors of the 75 line. The relay 109 is tuned to respond to alternating current of a frequency of 1300 cycles, relay 110 to current of a frequency of 1700 cycles and relay 111 to a current of another frequency, such as 16 cycles. 80

Upon the operation of relay 104, a circuit is established which may be traced from the source 107, inner armature and front contact of relay 104, ring conductor 112 of the line C, lower armature and back contact of relay 85 113, conductor 114, through the windings of relays 109, 110 and 111, conductor 115, upper armature and back contact of relay 113, tip conductor 116 of the line C, outer armature and front contact of relay 104, and thence 90 back through the source 108 to the other terminal of source 107.

Relays 109, 110 and 111 are of the acceleration type and may be of the particular type disclosed in Patent No. 1,607,910, granted to 95 Henry W. O'Neill, November 23, 1926.

Relays 109 and 110 being respectively responsive to currents of 1300 and 1700 cycle frequencies, operate, whereas relay 111 remains unoperated. 100

It is to be noted that the winding of switching relay 117 is normally shunted by the contacts of the relays 109 and 110 and that a complete electrical circuit normally exists from ground, through battery 119, resistance element 118, conductor 120, and then 105

in parallel through the circuit controlling elements 121 and 122 which are loosely mounted on the armatures of relays 109 and 110, respectively, to ground.

5 Relays 109 and 110, upon energizing, in the circuit previously traced, interrupt the circuits through the contacts 121 and 122, thereby removing the shunt from relay 117 and permitting relay 117 to operate in a 10 circuit traced from ground through battery 119, resistance element 118, and thence to ground through the winding of relay 117.

15 Relay 117 upon energization disconnects the line from the signal 125 at its armatures and back contacts and at its front contacts connects the 16-cycle current source 123 through the tip and ring cut-off contacts of jack 124 to operate the signal 125, which informs the operator at B that there is a call 20 awaiting her attention.

Upon noting the operation of signal 125, the operator at station B proceeds to answer the call in a well known manner by inserting plug 126 in jack 124.

25 It is desirable to avoid applications of ringing or low frequency signaling currents to a line circuit which may be equipped for superposed telegraph working, due to interference effects which may thereby be set 30 up in the telegraph receiving devices. In signaling from the point A, this is entirely met by absence of ringing current at the key 100 which merely applies battery current over the sleeve conductors of the connection for the control of the relay 104 in 35 connecting signaling currents of high frequencies only to the line conductors. The frequency of these currents is sufficiently high to entirely avoid interference with the 40 telegraph devices assumed as present on the line. The "cut-off" contacts of the key 100 disconnect the main conductors in excluding the signaling currents from equipment (not shown) which may be considered as 45 present at the left-hand side of the key 100.

50 In originating a call the operator at B inserts the plug 126 into jack 124 and operates the key 150 with which the 16-cycle current source 127 is associated. Upon the insertion of plug 126 into jack 124 the winding of the signal 125 is disconnected from the tip and ring contacts of jack 124. A 55 circuit is established which may be traced from the source 127, through the lower alternate contact of key 150, ring contacts of plug 126 and jack 124, the lower armature and back contact of relay 117, conductor 114, through the windings of relays 109, 60 110 and 111, conductor 115, upper armature and back contacts of relay 117, tip contacts of jack 124 and plug 126, and thence to ground at the upper alternate contact of key 150. Relays 109 and 110, being responsive 65 respectively to currents of 1300 and

1700 cycles, do not operate in this circuit, whereas relay 111, which is tuned to respond to application of 16-cycle current now energizes.

As described in connection with relay 70 117, it will be noted that relay 113 is shunted by the contacts 140 of the relay 111 and that a complete electrical circuit normally exists from ground through battery 129, resistance element 128, conductor 130, and 75 thence to ground through the contacts 140 of relay 111. Relay 111, in operating, interrupts the circuit just traced thereby removing the shunt from the winding of relay 113, whereupon this relay energizes in 80 a circuit extending from grounded battery 129, through the resistance element 128, and thence to ground through the winding of relay 113.

85 Relay 113 in operating connects the high frequency sources 131 and 132 which are connected in series, to the tip and ring conductors 116 and 112 of line C whereupon a circuit is established extending from the sources 131 and 132 over the armatures and 90 front contacts of relay 113, line conductors 116 and 112 of line C, the armatures and back contacts of relay 104, conductors 133 and 134, and thence in parallel through the filter amplifiers X and Y, which are adapted to respectively pass these frequencies, to the windings of relays 135 and 136. Relays 135 and 136 thereupon operate. The filter 95 amplifiers X and Y may be of any of the well known types and their functions and 100 operations are well known and need not be described here.

105 It will be noted that the switching relay 137 is normally operated over a circuit extending from grounded battery through the winding of relay 137, conductor 138, and thence in parallel to ground through the armatures and back contacts of relays 135 and 136. Relays 135 and 136 upon energizing 110 in the circuit previously traced interrupt the energizing circuit for relay 137 permitting this relay to retract its armatures and connect the 16-cycle current source 139 to the tip and ring contacts of jack 102 to actuate the signal 103. The operator at A, 115 upon noting the signal, answers the call in the usual manner.

120 In meeting the requirement relative to non-inclusion of low frequency or ringing current with the line C when signaling from the point B, advantage is taken of the quick response characteristics of the acceleration type relay 111 and also to the further phenomenon that a magnet will energize much 125 more quickly on removal of a shunt from its winding, than when the circuit of the magnet may be closed through any contact device. The latter feature is applied by provision of the resistance 128 to permit the contacts 140 of the relay 111 to normally 130

shunt the winding of the relay 113. Therefore, substantially the first half wave of current from the source 127 when applied through the key 150 effects translation to 5 cause the relay 113 to switch the conductors of the line C from the jack 124 to receive high frequency current from the sources 131 and 132. This sufficiently excludes the low frequency currents from the line C.

10 Referring now to Fig. 2, the operation of the circuit disclosed thereby is as follows:

Assuming that the operator at D desires to signal an operator at E over the transmission line F, she inserts plug 201 into 15 the jack 202 and actuates key 200. The insertion of the plug 201 into jack 202 disconnects the windings of the signal 203 from the tip and ring contacts thereof and in actuating key 200, a circuit is established 20 which may be traced from the 16-cycle current source 204, lower alternate contact of key 200, the ring contacts of plug 201 and jack 202, the lower armature and back contact of relay 205, the lower left-hand winding 25 of repeating coil 206, conductor 207 through the winding of the alternating current high speed relay 208, conductor 209, the upper left-hand winding of repeating coil 206, the upper armature and back contact of relay 205, the tip contacts of jack 202 and plug 201, and thence to ground 30 through the upper alternate contact of key 200.

The switching relay 210 is normally energized over a circuit extending from grounded battery through the winding of 35 relay 210, conductor 211, and thence to ground through the circuit controlling element 212 which is mounted on the armature of relay 208. Relay 208 in energizing in the circuit previously traced interrupts this energizing circuit for relay 210 and permits retraction of armatures of the latter relay. At its lowermost and middle armatures and back contacts, relay 210 connects the conductors 213 and 214 which are adapted to be associated with the 1300-cycle ringing current source 215, to the line conductors of the transmission line F, and 40 at its outermost armature and back contact establishes an energizing circuit for relay 216 which may be traced from grounded battery, through the uppermost armature and back contact of relay 210, conductor 217, winding of relay 216, and thence to ground 45 through the brush and live segments of interrupter 218. Relay 216 is intermittently energized in this circuit through the operation of the interrupter 218 and thereby intermittently connects the 1300-cycle current source 215 to the line conductors of the transmission line F through the conductors 214 and 213.

At the distant end of the transmission 50 line F a high speed relay 219 controls the

operation of switching relay 220 through the circuit controlling element 221.

Relay 239 is controlled by the operation of the circuit controlling element 221 which intermittently interrupts the normally existing circuit extending from grounded battery, resistance element 237 and thence to ground through the circuit controlling element 221. The intermittent interruption of this circuit causes the condenser 238 to charge and discharge to ground through 70 the winding of relay 239.

Upon the intermittent energization of relay 216, relay 219 is energized over a circuit which may be traced from the 1300-cycle 75 source 215, outer armature and front contact of relay 216, conductor 213, lowermost armature and back contact of relay 210, the ring conductor of the line F, lowermost armature and back contact of relay 224, the 80 lower left-hand winding of repeating coil 225, conductor 226, the winding of relay 219, conductor 227, upper left-hand winding 85 of repeating coil 225, the middle armature and back contact of relay 224, the tip 90 conductor of line F, middle armature and back contact of relay 210, conductor 214, inner armature and front contact of relay 216 to the 1300-cycle source 215. Relay 219 is energized in this circuit and upon the 95 vibration of its armature interrupts the normally existing circuit including the resistance element 237, whereupon relay 239 becomes energized. It will be noted that relay 241 is normally energized over a circuit 100 extending from grounded battery through resistance element 240 and thence to ground through the winding of relay 241. The energization of relay 239 as above described, shunts relay 241 whereupon a circuit is established 105 extending from grounded battery, through the winding of relay 220, conductor 223 and thence to ground through the back contact and armature of relay 241. Relay 220 upon energization disconnects the 110 line from the signal 230 at its armature and back contacts and at its front contacts connects the 16-cycle current source 228 to the tip and ring contacts of jack 229 to operate the signal 230 associated therewith. 115

Upon noting the operation of signal 230, the operator at E proceeds to answer the call as before.

In order to describe the signaling operation over the transmission line F in the opposite direction, it will now be assumed that the operator at E desires to signal the operator at D. The plug 231 is inserted in jack 229 and key 250 is actuated. The insertion of plug 231 into jack 229 removes 120 the windings of signal 230 from the tip and ring contacts of jack 229 and by the actuation of key 250, a circuit is established which may be traced from the 16-cycle current source 232, the lower alternate contact of 125 130

key 250, ring contacts of plug 231 and jack 229, lower armature and back contact of relay 220, lower right-hand winding of repeating coil 225, conductor 233, through the 5 winding of relay 234, conductor 235, upper right-hand winding of repeating coil 225, upper armature and back contact of relay 220, tip contacts of jack 229 and plug 231, and thence to ground through the upper alternate contact of key 250.

Relay 234, upon energizing, causes its circuit controlling element 236 to vibrate whereupon the normally completed circuit extending from grounded battery through 15 the resistance element 280, conductor 281, and thence to ground through the circuit controlling element 236, is interrupted, thereby removing the shunt from relay 224 and permitting this relay to operate in a 20 circuit extending from grounded battery, resistance element 280, conductor 242, thence to ground through the winding of relay 224.

Relay 224, in operating, establishes a circuit extending from grounded battery 25 through the uppermost armature and front contact of relay 224, conductor 243, winding of relay 244, and thence to ground through the brush and live segments of interrupter 245. At its innermost armatures and front 30 contact, relay 244 connects the conductors 246 and 247 which are normally associated with the 1700-cycle current source 248 to the tip and ring conductors of the transmission line F. By the intermittent operation of relay 244, through the interrupter 245, the 1700 and 1300-cycle sources 248 and 249, respectively, are alternately applied to the line F to actuate high speed relays 270 and 251 over a circuit including the conductors 246 35 and 247, the innermost and middle armatures and front contacts of relay 224, the line conductors of the line F, the middle and lowermost armatures and front contacts of normally operated relay 210, conductors 252 40 and 253 and thence in parallel through the windings of relays 270 and 251. Relays 270 and 251 are respectively responsive to alternating current frequencies of 1700 and 1300 45 cycles.

It will be noted that one winding of polarized relay 255 is normally shunted by the circuit from the resistance element 256 through the circuit controlling element 257 of relay 270 and the other winding is normally 50 shunted by the circuit from resistance element 258 through the circuit controlling element 259 of relay 251.

Relays 270 and 251 are intermittently operated in the circuit previously traced, thereby alternately removing the shunts to permit the windings of relay 255 to be alternately energized. The armature of relay 255, being intermittently actuated, alternately connects ground and battery to the 55 winding of relay 282 and the condenser 260,

whereupon the condenser 260 charges and discharges through the winding of the alternating current relay 282. Relay 282 thereupon energizes and establishes a circuit extending from grounded battery through the 70 winding of relay 205, conductor 261, and thence to ground through the armature and front contact of relay 282. Preferably the relay 282 should have a natural period corresponding with the changes produced by 75 the distant interrupter 245.

Relay 205 on energizing connects the 16-cycle current source 262 to the tip and ring contacts of jack 202 to actuate the signal 203 associated therewith.

Upon noting the operation of signal 203, the operator at D proceeds to answer the call in the usual manner.

What is claimed is:

1. In a signaling system, a transmission line, a plurality of alternating current sources, means for simultaneously applying currents from said sources to the line, a bridge across the line comprising means responsive respectively to said simultaneously applied current from said sources, and current supplying means including a source of current and a relay, said relay being controlled by said responsive means to apply current from said source to said line.

2. In a signaling system, a transmission line having a sending and receiving station at each end thereof, a plurality of alternating current sources, means at both stations each means independent of the other being adapted to apply currents from said sources simultaneously to the line, a signal at each station, and a bridge across the line at each station comprising means responsive to simultaneously applied currents from the sources at the sending station at one end of the line to actuate the signal at the receiving station at the other end of the line.

3. In a signaling system, a transmission line, a plurality of alternating current sources means for simultaneously applying currents from said sources to the line, a high impedance bridge across the line comprising means responsive respectively to currents from said sources, and current supplying means including a source of current and a relay, said relay being controlled by said responsive means to apply current from said last mentioned source to said line.

4. In a signaling system, a transmission line, a plurality of alternating current sources, means for simultaneously applying currents from said sources to the line, a high impedance bridge across the line comprising means independently responsive to the respective currents from said sources and connected in a serial relation to each other in said bridge, and current supplying means including a source of current and a relay, said relay being controlled by said responsive

means to apply current from said last mentioned source to said line.

5. In a signaling system, a transmission line, a plurality of alternating currents of different frequencies, means for simultaneously applying currents from said sources to the line at either one or the other end thereof, means at both ends of the line each responsive to said simultaneously applied currents from the opposite end of the line, and signaling means at both ends of said line each adapted to be actuated by the corresponding responsive means.

6. In a signaling system, a transmission line, a plurality of sources of alternating current of different frequencies, means for simultaneously applying currents from said sources to said line, means responsive to said currents comprising a relay responsive to each of said currents, and a signaling means including a signaling current source and a relay, said relay being responsive to the simultaneous operation of said relays to apply current from said signaling current source to said line.

7. In a signaling system, a transmission line, a plurality of sources of alternating current of different frequencies, a switching means, means actuated by said switching means to simultaneously apply currents from said sources to said line, and signaling means including a signaling current source and a relay, said relay being responsive to the simultaneous application of said alternating currents to apply current from said signaling current source to said line.

8. In a signaling system, a transmission line, sources of current of different characteristics, a corresponding plurality of selectively responsive means and signaling means including a source of signaling current and a relay, said relay being under the joint control of said means for applying signaling current to said line.

45 9. In a signaling system, a transmission line, sources of current of different characteristics, a plurality of high speed relays selectively responsive to said currents and signaling means including a source of signaling current and a relay, said relay being under the joint control of said relays to apply current from said signaling current source to said line.

55 10. In a signaling system, a transmission line, sources of current of different characteristics, a corresponding plurality of high speed relays selectively responsive to said currents, a source of current of another different characteristic, a relay responsive to a current from said last mentioned source, a source of signaling current under control of said relay and means under the joint control of said high speed relays for applying current from said second mentioned source for the control of said last relay to apply current

from the signaling current source to the line.

11. In a signaling system, a source of low frequency alternating current, a transmission line, a plurality of alternating current sources of different frequencies, switching means for simultaneously applying currents from said alternating current sources of different frequencies to the line, and high speed relay means responsive to said low frequency current to control said switching means.

12. In a signaling system, a transmission line, sources of current of different characteristics at one end of the line, a low frequency alternating current source at the opposite end of the line, a plurality of high speed relays selectively responsive to said currents of different characteristics, and means responsive to the simultaneous operation of said relays to effect the disconnection of the opposite end of the line and the connection thereto of said low frequency source.

13. In a signaling system, a transmission line, sources of high and low frequency currents, switching means, and means simultaneously accelerated by a group of high frequency currents or by a low frequency current to control said switching means to transfer said line in the first instance from connection with said group of high frequency current sources into connection with a low frequency source, and in the second instance from connection with the first mentioned low frequency current source into connection with a second group of high frequency current sources.

14. In a signaling system, a transmission line, one end terminating in tip, ring and sleeve conductors at a sending station and the other end terminating in a receiving station, a signal normally connected to the line at the receiving station, a source of current at the receiving station, and means controlled over the sleeve conductor at the sending station to disconnect the signal from the line and to connect said current source to the signal for the operation thereof.

15. In a signaling system, a transmission line, one end terminating in tip, ring and sleeve conductors at a sending station and the other end in a receiving station, a plurality of sources of audible frequency currents, means controlled over the sleeve conductor of the line to simultaneously connect said current sources to the tip and ring conductors of the line, and means at the receiving station for translating said currents into a signal at the receiving station.

16. In a signaling system, a transmission line, one end terminating in tip, ring and sleeve conductors at a sending station and the other end in a receiving station, a signal at the receiving station, means controlled over the sleeve conductor of the line to super-

5 impose currents of different characteristics on the tip and ring conductors of the line, and a plurality of electromagnetic devices selectively responsive to the currents of different characteristics to effect the operation of the signal at the receiving station.

10 17. In a signaling system, a transmission line, a sending station, a receiving station having a signal thereat, a high speed relay at the sending station having a circuit controlling element, a switching relay normally shunted by said circuit controlling element, sources of high frequency current of differ-

ent frequencies, means at said sending station for actuating said high speed relay 15 whereby the shunt is removed from the switching relay, and means responsive to the operation of said switching relay for applying said high frequency currents to the line simultaneously to actuate the signal at the 20 receiving station.

In witness whereof, I hereunto subscribe my name this 17th day of November A. D., 1922.

HENRY W. O'NEILL.
